US0D1101380S

(12) **United States Design Patent** (10) **Patent No.:** **US D1,101,380 S**
(45) **Date of Patent:** **** Nov. 11, 2025**

(54) **SHOE SOLE**

(71) Applicant: **ON CLOUDS GMBH**, Zürich (CH)

(72) Inventor: **Timon Kuhlenkamp**, Zürich (CH)

(73) Assignee: **ON CLOUDS GMBH**, Zürich. (CH)

(**) Term: **15 Years**

(21) Appl. No.: **29/949,840**

(22) Filed: **Jun. 28, 2024**

Related U.S. Application Data

(62) Division of application No. 35/518,319, filed on Mar. 9, 2023 (U.S. filing date under 35 U.S.C. 384), and having an international filing date of Mar. 9, 2023, now Pat. No. Des. 1,055,483.

(57) **CLAIM**

The ornamental design for a shoe sole, as shown and described.

DESCRIPTION

FIG. 1 is a perspective view of a shoe sole, showing the design;

FIG. 2 is a front view of a shoe sole;

FIG. 3 is a back view of a shoe sole;

FIG. 4 is a right view of a shoe sole;

FIG. 5 is a left view of a shoe sole;

FIG. 6 is a top view of a shoe sole; and,

FIG. 7 is a bottom view, of a shoe sole.

The dashed lines are included for the purpose of showing environmental structure as well as portions of the shoe sole that form no part of the claimed design.

1 Claim, 7 Drawing Sheets
